CLAIM

The ornamental design for a shareable apple box, as shown and described.

DESCRIPTION

FIG. 1 is a front, left, and top perspective view of a sharable apple box in accordance with the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an exploded view thereof; and,

FIG. 9 is a semi-exploded view thereof.

The broken lines in the drawings depict environmental subject matter and form no part of the claimed design.
